CLAIM

The ornamental design for pants with rear lower mesh portion, as shown and described.

DESCRIPTION

FIG. 1 is a front perspective view of a new design for pants with rear lower mesh portion.

FIG. 2 is a rear perspective view of a new design for pants with rear lower mesh portion.

FIG. 3 is a front view of a new design for pants with rear lower mesh portion.

FIG. 4 is a rear view of a new design for pants with rear lower mesh portion.

FIG. 5 is a left side view of a new design for pants with rear lower mesh portion.

FIG. 6 is a right side view of a new design for pants with rear lower mesh portion.

FIG. 7 is a top view of a new design for pants with rear lower mesh portion; and,

FIG. 8 is a bottom view of a new design for pants with rear lower mesh portion.

The broken lines shown in the drawings depict portions of the pants that form no part of the claimed invention. The line dot-dot line broken lines in the drawings represent the boundaries of the claim and form no part of the claimed design.
